UNITED STATES PATENT OFFICE

129,752

DESIGN FOR A COMBINATION RADIATOR, HOOD AND FENDERS FOR VEHICLES

Donald G. Renno, Fort Wayne, Ind., assignor to
International Harvester Company, a corpora-
tion of New Jersey

Application July 10, 1940, Serial No. 93,524

Term of patent 7 years

To all whom it may concern:

Be it known that I, Donald G. Renno, a citizen
of the United States, residing at Fort Wayne, in
the county of Allen and State of Indiana, have
invented a new, original, and ornamental Design
for a Combination Radiator, Hood, and Fenders
for Vehicles, of which the following is a speci-
fication, reference being had to the accompanying
drawing, forming part thereof, in which:

Figure 1 is a three-quarter front perspective
view of a combination radiator, hood, and fenders
for a vehicle, showing my new design;

Figure 2 is a full front perspective view of the
same; and,

Figure 3 is a diagrammatic top plan view of
the same shown on a somewhat reduced scale.

I claim:

The ornamental design for a combination radi-
ator, hood, and fenders for vehicles, substantially
as shown.

DONALD G. RENNO.
